UNITED STATES PATENT OFFICE.

LUTHER A. WATTERS, OF ST. LOUIS, MISSOURI, ASSIGNOR TO UNITED ACCOUNTING MACHINES, INCORPORATED, A CORPORATION OF DELAWARE.

AUTOMATIC POSTING MACHINE.

Application filed June 21, 1920. Serial No. 390,451.

To all whom it may concern:

Be it known that I, LUTHER A. WATTERS, a citizen of the United States, and residing at St. Louis, Missouri, have invented the 5 new and useful Improvements in Automatic Posting Machines, of which the following is a specification.

This invention relates to a machine adapted to mechanically post accounts.

10 One of the objects of this invention is to provide a machine whereby a given account may be posted mechanically so as to practically eliminate manual operations and complications.

15 Another object is to provide a machine of the character referred to, which will not only post the account on a statement, but also on a ledger sheet.

Another object of this invention is to provide 20 a machine of the character referred to, in which a series of items related to a principal item may be automatically posted and may be posted concurrently with the principal item.

25 Another object is to provide a machine of the character referred to, with selective manipulative means, whereby a given item and also the items relating thereto, may be found and posted.

30 Further objects will appear from the detail description taken in connection with the accompanying drawings, in which:

Figure 1 is a plan of a machine embodying this invention;

35 Figure 2 is a section on the line 2—2, Figure 1;

Figure 3 is a detail of the locating members;

Figure 4 is a plan of Figure 3;

40 Figure 5 (Sheet 4) is a detail of Figure 3;

Figure 6 (Sheet 5) is a section on lines 6—6, Figures 4 and 5;

Figure 7 is a detail side elevation, partly in section, showing the primary locating mechanism;

Figure 8 is a detail plan, partly in section, on the line 8—8, Figure 7;

Figure 9 is an enlarged detail of Figure 7;

45 Figure 10 is a detail rear elevation of Figure 7, showing the selective manipulative mechanism;

Figure 11 is a section on the line 11—11, Figure 10;

50 Figure 12 is a detail of the selective ma-

nipulative mechanism, showing the interior construction;

Figure 13 is a side elevation, partly in section, showing the secondary locating mechanism;

60

Figure 14 is a plan of Figure 13, partly in section, on the line 14—14, Figure 13;

Figure 15 is an enlarged detail of Figure 13;

65

Figure 16 is a side elevation, partly in section, showing the tertiary locating mechanism;

70

Figure 17 is a plan of Figure 16, partly in section, on the line 17—17, Figure 16;

Figure 18 is a detail of Figure 16;

75

Figure 19 is a rear elevation of Figure 18;

Figure 20 is a plan showing the platen operating mechanism;

Figure 21 is an enlarged detail of Figure 20, taken on the line 21—21, Figure 20;

75

Figure 22 is a section on the line 22—22, Figure 21;

Figure 23 is an enlarged section on the line 23—23, Figure 20;

80

Figure 24 is a detail side elevation of the carriage, its platen, and the operating mechanisms therefor;

Figure 25 is a detail plan of Figure 24;

Figures 26 to 33 inclusive are views similar to Figures 24 and 25, but showing the parts in different positions;

85

Figure 34 is a plan of the motor drive mechanism for the carriage;

Figure 35 is a section on the line 35—35, Figure 34;

90

Figure 36 is a side elevation of the restoring mechanism taken from the right side on the line 36—36, Figure 1;

Figure 37 is a similar view from the left side on the line 37—37, Figure 1; and

95

Figure 38 (Sheet 5) is a face view of a statement or ledger sheet showing the entries thereon.

In many of the views, parts have been omitted; this has been done to promote clearness, for if all parts behind the plane at which a given view is taken were shown, it would obscure the particular mechanism under consideration.

In the drawings is shown an embodiment 105 of this invention as exemplified in a machine for posting taxes. It should, however, be understood that this embodiment is simply an example of various kinds of uses and embodiments to which this invention 110

may be applied. It will, therefore, be well to just briefly describe the prior methods of entering taxes.

In the prior method of making up tax books and receipts in tax offices, it is the practice of one auditor to call the valuations of the taxes of a given tax payer to a certain party, who in turn, locates the valuation on a tax computing table. In these tax computing tables, the principal items or the tax valuations are arranged in a column, while the different taxes, such as county, State, school taxes, etc., and the totals corresponding to these items, are entered in columns, so that the taxes for a given principal item or valuations are arranged in a line. Accordingly, the second auditor referred to when a valuation is called, locates the valuation on the tax computing table, holding a rule from the location of the valuation across the table to the total valuation of the taxes at the end of the line. The second auditor will then call out to a third auditor or poster, the amount of the individual taxes under the different classes, and these taxes as well as the total are then entered into the ledger and onto the statement. It will, of course, be obvious that such hand method is not only laborious, but also is liable to cause errors in the entrance of the taxes both in the ledger and on the statement.

In accordance with the specific embodiment of this invention, the tax computing table is set on a printing bed, so that there will be printing lines and columns corresponding to the principal items or tax valuations and the related items or taxes and the totals corresponding to the principal items. A carriage is provided which is arranged to travel over the bed so as to align a platen with a given line of type corresponding to a given principal item or tax valuation and its related items or the taxes and totals corresponding to that valuation. Upon cooperation of the platen and the type, the tax valuation as well as the various taxes and the total will be printed on a sheet on the platen so as to record the same.

A key board is provided which controls the travel of the carriage, so that upon depression of keys corresponding to the principal item or tax valuation, the carriage will be located in order to position the platen in proper cooperative relation with the printing line containing the principal item and the related items.

The carriage is provided with two platens, namely a main platen for receiving the statement, and a supplemental platen for receiving the ledger sheet. After the entry of the principal and related items on the statement on the main platen, the carriage moves so as to position the supplemental platen in proper cooperative relation

with the printing line, so as to cause entry on the ledger of the principal and related items.

The frame, printing bed, and carriage.

70

Referring to Figures 1, 2, and 38, 1 designates a base which is provided with suitable sides 2, ends 3 and 4, a rear wall 5, a cover 6, brackets 7 and 8, a bed 9, and a shelf 10. The frame may be made in any suitable manner and of any suitable material so as to form a rigid structure.

The bed 9 is formed with a transverse dove-tailed groove 11 at its forward end extending transversely of the bed, the rear end of the bed being provided with a similar groove. Arranged on the bed are strips 12 which carry the type 13, and which strips are secured in place by headed shanks 14 taking into the grooves 11 and holding the strips in place. The type may be of any suitable form, such as embossed type, or any other form adapted for cooperation with a platen.

When a series of type strips are secured on the bed, they are arranged to form columns and lines of type, the columns extending along the bed, and the lines across the bed so as to form, for instance, a computing table such as used for the entering of taxes. Accordingly, an end column, such as the right column Figure 1, will contain the principal item, such as the tax valuations, while the other columns will contain the related items, such as the different taxes and the totals corresponding to the principal items, and the related items corresponding to a principal item will, therefore, be arranged in a line with the principal item. The principal items will, of course, be in the decimal system, but in view of the fact that the principal items in practice are varied in steps of five dollars, the line varies in units of five.

Arranged along the sides 2 are tracks 15 which receive groove rolls 16 of a carriage arranged to travel along the printing bed. This carriage comprises a body of end plates 17 connected by shafts 18 and 19 on which the rolls 16 are mounted, this carriage being otherwise braced by cross bars as hereinafter described, to form a rigid structure. The carriage has mounted thereon a main platen M and a supplemental platen S, these platens extending across the printing bed and along the printing lines. The carriage has also mounted thereon pairs of latches 20 and 21 for a purpose hereinafter to be described, the main latches 20 corresponding to the main platen, while the supplemental latches 21 corresponding to the supplemental platen, there being a main latch and a supplemental latch at each end of the carrier, and these latches being pivoted for vertical movement as hereinafter described.

110

115

120

125

130

The carriage is normally in the position shown in Figure 1 with the main platen M at the "0" position, and motor mechanism hereinafter to be described exerts a yielding tension on the carriage, tending to move it rearwardly or to the right, Figure 1, along the table. In order to maintain the plateaus parallel with the printing lines, a justifying mechanism is provided, comprising racks 22 mounted on ribs 23 projecting laterally from the sides 2 and supporting the tracks 15 as well as the racks 22. These racks mesh with pinions 24 fixed to the shaft 19 which is mounted for rotation in the end plates 17.

15   *The primary locating mechanism.*

Referring to Figures 1, 2, 3, 4, 5, 6, 7, 8 and 9, mounted for sliding movement on the ribs 23 (see Figure 6) are a pair of locating members or bars 30 which have, at their forward ends, depending brackets 31 connected by a cross bar 32. We will, however, assume in the discussion of the primary locating mechanism that the bars 30 are retained against movement. Each of these bars is provided with a series of notches 33 adapted to receive the latches 20 (and also the latches 21), it being noted that the rear side of each notch is vertical, while the forward side is inclined or beveled and that the tips of the notches are correspondingly shaped.

The notches 33 are in this embodiment uniformly spaced along the bars and are ten in number corresponding to the ten primary positions, such as "0", "100", "200", "300", "400", "500", "600", "700", "800", and "900". In order to firmly hold the bars in position, they may be grooved as shown in Figure 6 to receive plates 34 clamped to the ribs 23.

Mounted inside of and arranged along the locating bars 30 are movable bars 35, these movable bars being mounted on the ribs 23 by screws 36 engaging slots 37 in the bars 35, the latter being frictionally held against movement by friction washers 38. The upper faces of the bars 35 are flush with the upper faces of the bars 30 and they are also provided with notches 39, there being in this embodiment ten of such notches spaced uniformly along each bar. The spacings of the notches 39 are, however, less than the spacings of the notches 33 and in this embodiment, using the decimal system, the distance between two adjacent notches 39 is nine-tenths of the distance between two adjacent notches 33. Accordingly, the spacings of the locating elements on the movable bar 35 is a definite fraction of the spacings of the locating elements on the locating bar 30, the definite fraction having for a numerator, a number which is one less than the number of spacings of the first elements and whose denominator is the number of spacings of the first element; or the

numerator is the length of the locating bar as measured between its extreme end spacings and the denominator is the length of the movable bar also measured between its extreme notches. Accordingly, as shown in Figures 3 and 4, when the first notches on the bars are in alinement, the nine notches will be nine steps out of alinement, while all of the other notches will be out of alinement, progressively one, two, etc., steps. 75

It will be noted that the bars 35 terminate short of the forward ends of the bars 30. Mounted to slide on the terminals of the bars 30 are a pair of side members 40 having ribs 41 engaging corresponding grooves in the bars 30, so that the side members 40 are guided on the bars 30, and in the normal position of the parts, the side members 40 will butt against the ends of the movable bars 35 as shown in Figures 3 and 4. The side members 40 are connected by a cross bar 42 which ties them together and holds the side members 40 against the bars 30.

Mounted on the frame are a pair of side plates 43 which are connected by cross bars 44 and 45 and a cross bar 46 slotted to form a comb-like structure. Mounted to slide on the cross bars 44 and 45 and in the recesses of the cross bar 46 are a series of ten primary stops 47, each of which is connected by springs 48 with the cross bar 44 so that the stops 47 are normally retained in elevated positions. It will be understood that the stops 47 are additionally retained in properly spaced relation other than by the slotted cross bar 46 by spacing collars on the cross bars 44 and 45. 95

Each stop 47 has a beveled shoulder 49 adapted to be engaged by a latch bar 50 mounted on a pair of arms 51 fixed to a shaft 52, the latch bar 50 being beveled as shown in Figure 9. This latch bar is maintained under the tension against the shoulders by a spring 53 anchored to one of the side plates 43 and connected with an extension on one of the arms 51. 100

A bar 54 extends underneath shoulders 55 formed on the stops 47 and this bar is mounted in a pair of arms 56 on a rock shaft 57 mounted in the side plates 43. One of these arms 56 has an extension 58 provided with a beveled face 59 in the path of a pin 60 on an arm 61 pivoted on a lug 62 on the base and provided with an extension 63 engaging a pin 64 on the cross bar 42 connecting the side members 40. The arm 58 is normally held against the stop 65 on the side plates 43 by a spring 66. The cross bar 42 (Figure 2) is also connected to a tension spring 67 anchored on the frame, which spring tends normally to move the cross bar and the side members 40 connected therewith to the right Figures 2 and 7. 115

In the normal position of parts, the first 120

or "0" notches or locating elements on the bars 30 and 35 are in alinement and are engaged by the main latches 20 so as to maintain the main platen M in "0" position. At 5 this time, the arm 61 is maintained in "0" position by the engagement of the pin 60 behind the arm 58. Let us assume now that the third or "2" stop 47 is depressed. Upon the depression of this "2" stop, the lower 10 end thereof will be projected beyond the cross bar 46 from a position where it clears the arm 61 to a position where it is in the path of that arm. The engagement of the shoulder 55 on the depressed stop 47 with the 15 cross bar 54 will move the arm 58 to dotted position (Fig. 7), thereby moving it out of the path of the pin 60 on the arm 61 so that the spring 67 will move the side members 40 to dotted position until the arm 60 is arrested by the "2" stop. As the stop is fully 20 depressed, it will be latched by the latch bar 50 so that this stop will remain latched in depressed position even if pressure on the stop is removed.

25 As the side members 40 move to the right, Figs. 2 and 7, they will in bearing against movable bars 35, shift these bars along the bars 30 for a distance sufficient to cause the "3" notch or locating element 39 to aline 30 with the "3" notch or locating element 33, while all of the other notches will be out of alinement. Now the movement of the bar 35 will cause the main latches 20 to be raised out of the "0" locating notches 33 and 39 35 whereby the carriage is released. This carriage will now under the action of its yielding- 40 ingly acting motor move to the right Figure 2 until the main latches 20 reach the alined "3" notches or locating elements when 45 these main latches will drop into these notches so as to primarily locate the carriage. This carriage is, therefore, located with the main platen M along and in co-operative relation with the line of type corresponding to the principal item "200" and the related items on the same line.

The secondary locating mechanism.

50 Referring to Figures 1, 2, 3, 4, 13, 14, and 15, the side plates 43 have mounted thereon cross bars 70 and on these cross bars are mounted plates 71 which are connected by side bars 72. The plates 71 may also be connected by bars 73 so as to form together 55 with the bars 72 a frame mounted on a bar 70 as hereinafter described. Slidably mounted upon the bar 72 are stops 74, there being in this case also a series of ten-secondary stops. These stops are properly spaced 60 by collars 69 on the bar 72 and are retained in normal raised position by springs 75 anchored to the bars 72 and connected with the stops.

65 Each stop has a shoulder 76 arranged for cooperation with a cross bar 77 mounted on

arms 78 fixed to a rock shaft 79, one of these arms having an extension 80 connected with a spring 81 anchored on one of the plates 71. The function of the shoulder 76 and cross bar 77 is similar to the function of the 70 shoulder 49 and the cross bar 50 heretofore described, namely to latch the stops in depressed position against the tension of the springs 75.

75 Each stop has a shoulder 82 arranged to engage a cross bar 83 carried by arms 84 fixed to a rock shaft 85 mounted in the plates 43, one of the arms having an extension 86 provided with a beveled portion 87 in the path of a pin 88 on an arm 89 80 pivoted on a bracket 90 on the frame and provided with an extension 91 connected with a pin 92 on the cross bar 32. A spring 93 connected with an extension on the arm 86 and anchored on the plate 43 normally 85 operates to hold the arm with its tip in front of the pin 88, the frame being arrested by one of the cross bars 70. The arm 89 is, therefore, held in normal or "0" position, but when released will travel underneath the 90 stops 74 and if one of these stops is depressed into the path of the arm, it will be arrested.

Assuming that the carriage has been located in the primary position by the alined 95 "3" locating elements 33 and 39 as heretofore described, at which time the tension exerted on the carriage by the motor mechanism will exert through the engagement of the main latches 20 with the locating elements 100 or notches in the bars 30, a tension on the bars 30 and 35 to the right, Figure 13 and assuming also that at this time secondary "9" stop 74 is depressed so as to cause it to project to dotted position, Figure 105 13, in the path of the arm 89 and become latched in that position the following operation will take place.

The engagement of the shoulder 82 with the cross bar 83 will move the arm 86 to 110 dotted position, Figure 13, so as to move it out of the path of the pin 88 on the arm 89, thereby releasing this arm and causing it to move to dotted positions, Figures 13 and 14, until arrested by the "9" secondary stop 115 74 as shown. Accordingly, the bars 30 and the bars 35 frictionally connected therewith will move forwardly with the carriage to nine division of the space between the primary notches 33, so that the main platen 120 will now be positioned along the line of type on the printing bed identified by the principal item "290" as noted, also in dotted positions, Figures 26 and 27. Accordingly, the main platen will be secondarily 125 positioned.

The tertiary locating mechanism.

The primary and secondary locations are each ten in number corresponding to the 130

decimal system. Accordingly, there are ten primary positions as determined by the ten notches 33 and 39 and the ten stops 47, and there are ten secondary positions as determined by the ten stops 74. In view of the fact, however, that in this particular embodiment the principal items need be determined only in units of five, there is only an intermediate tertiary position between any two secondary positions.

Referring to Figures 1, 2, 3, 4, 16, 17, 18 and 19, as previously described, the stops 74 are mounted in a frame, comprising, the bars 70 and 73 and the plates 71, and this frame is mounted for endwise movement on the bar 70, this frame carrying rolls 100 engaging the lower bars 70 to permit such movement. Springs 101 connecting a bracket 102 with one of the plates 71 normally tend to move this frame to the left, Figure 19, but this frame is normally retained in full line position, Figure 18, by a latch 103 mounted on a rock shaft 104 in the plates 43 and arranged to take in front of one of the plates 71. The rock shaft 104 has an arm 105 connected with a spring 106 anchored on one of the plates 43 and holding the arm 105 against a stop 107 with the latch 103 in front of the plate 71. The latch 30 and plate have cooperating beveled portions 108 and 109. Accordingly, when the latch is moved to dotted position, Figure 18, the springs 101 will move the frame carrying the stops 74 one-half step until the frame 35 is arrested by the side plate 43.

Assuming that the main platen has been primarily located at "290" through the primary and secondary locating mechanism as heretofore described, upon actuation of the latch 103 (releasing the frame carrying the stops 74 and causing these stops 74 to be carried onward a half space, the onward movement of the depressed stop 74 engaged by the arm 89 being followed by the arm under the tension exerted on the carriage) will cause the carriage to be moved onward one-half step so as to position the main platen at "295" as shown in full line position, Figures 28 and 29. Accordingly, the main platen will be tertiary located along the line of type identified by the principal item "295". Of course, in the particular embodiment described, there is only one tertiary location intermediate the spacings of each secondary location. This is, however, only for the reason that only one such intermediate tertiary location is necessary in this particular embodiment, and it will be obvious that a series of tertiary locations may be readily obtained.

The selective manipulative mechanism.

Referring to Figures 1, 2, 7, 10, 11, 12, 13 and 16, the key board in this particular embodiment comprises ten keys. Accord-

ingly, it is necessary to provide shiftable transmission mechanism between the keys and the stops in order to permit the same set of keys to be utilized for primary, secondary and tertiary locations. Each key 70 115 has a shank passing through a plate 116 on the frame and a slotted guide 117 connecting the side plates 43. The key shanks are engaged by a cross bar 118 mounted in arms 119 fixed to the rock shaft 75 120 mounted in the plates 43, and a spring 121 connected with an extension on one of the arms 119 and anchored on one of the plates 43, normally holds these keys in raised position.

Mounted below the key shanks is a transmitter carrier 122 provided with rolls 123 projecting through and guided in slots in the plates 43 so that the carrier will move forward and backward. The carrier has 85 mounted therein a series of ten plungers 124, arranged below and in alinement with the key shanks and normally held in raised position by springs 125. These plungers 124 are arranged to be successively alined with 90 lugs 126 on the primary stops 47 and lugs 127 on the secondary stops 74. The plunger opposite and engaged by the "5" key is also arranged to engage an arm 128 fixed to the rock shaft 104.

The carrier 122 is engaged by an arm 129 pivoted on one of the plates 43 and connected with a spring 130 anchored on the plate. Accordingly, the spring 130 tends to move the carrier to the left, Figure 7. This carrier is provided with three stops 131, 132, and 133 arranged to be engaged by pawls 134 and 135 pivoted at 136 on the plate 43 and connected by a spring 137. These pawls have extensions 138 and 139 embracing a pin 140 on an arm 141 fixed to the rock shaft 120.

In the normal position of parts as shown in Figure 12 and full line position Figure 7, the carrier will be arrested by the pawl 134 engaging the first stop 131, it being noted that the pawl 134 is slightly longer than the pawl 135. Accordingly, the carrier will be located with the plungers 124 thereon in alinement with the lugs 126 on the primary stops 47. Therefore, upon depression of any key such as the "2" key, the corresponding primary stop will be depressed so as to cause primary location of the main platen as heretofore described. Upon such depression of a key, the pawl 134 will move out of the path of the first stop 131 so that the spring 130 will move the carrier forwardly but only a slight distance. As the key is released causing it to rise under the tension of the spring 121, it being noted that the depressed stop has been latched in depressed position, the spring 121 will return the pawl, but since the carrier has shifted so that the stop 131 is behind the tip of the pawl 134, the spring 137 will 110 115 120 125 130

yield, and as the pawl 136 moves out of the path of the stop 131, the carrier is moved forwardly until the second stop 132 engages the pawl 134, thereby locating the carrier 5 with the plungers thereon in alinement with the lugs 127 on the secondary stops 74, as shown in full lines Figure 13.

Upon the depression of any key, such as the "9" key, Figure 13, through the medium 10 of the corresponding plunger, the corresponding "9" stop will be depressed and latched in depressed position thereby secondarily locating the main platen as heretofore described. Upon the secondary actuation 15 of the key and upon return thereof, the plunger carrier will again be shifted until arrested by the engagement of the third stop 133 with the pawl 134, thereby locating the "5" plunger opposite the arm 128 as shown 20 in Figures 16 and 18.

Upon the depression of the "5" key, it will operate through the corresponding plunger to shift the latch 103, thereby releasing the frame carrying the secondary 25 stops 74 so as to permit this frame and the depressed secondary stop to shift a sufficient distance onward to locate the main platen in tertiary position as heretofore described. It will be noted that the third stop 133 is 30 extended as shown in Figure 12, so that the plunger carrier will not be further shifted upon depression of the tertiary depressed key as it is wholly unnecessary to further shift the same.

35 *Platen operating mechanism.*

Referring to Figures 1, 2, 20, 21, 22, and 23, the sides 2 of the frame have mounted thereon brackets 150 upon which are mounted 40 rock shafts 151 extending along the machine. These rock shafts have fixed thereto arms 152 which carry bars 153 also extending along the machine for a purpose to be hereinafter described. The rock shafts 151 have arms 154 slotted to receive pins 155 on 45 a rock shaft 156 mounted in brackets 157 on the machine frame at the forward end of the machine, and this rock shaft has fixed thereto a handle 158 projecting through the 50 top 6 and connected with a spring 159 anchored on the frame.

The spring 159 normally holds the parts in full line position Figures 21, 22 and 23. When, however, the handle 158 is pulled 55 forwardly, the bars 153 will be moved down to dotted position so as to actuate the platen mechanism as hereinafter described.

The platens.

60 Referring to Figures 1, 2, 24, 25, 30 and 31, fixed to a shaft 160 in the end plates 17 of the carriage is a frame 161 carrying the main platen M and this frame has arms 162 connected with springs 163 anchored on the 65 end plates 17 so as to normally maintain

the platen frame elevated as shown in Figures 2 and 24.

Mounted for vertical sliding movement on the end members 17 of the carrier are a pair of slides 164 which have laterally turned lugs 165 in the path of the bars 153. Pivoted at 166 to these slides are a pair of arms 167, the tips of which are arranged to engage pins 168 on arms 169 fixed to the rock shaft 160 on which the frame 161 is 70 also fixed. The arm 167 is connected by a link 170 with an arm 171 fixed to the rock shaft 172 on which the latches 20 are fixed. The construction is such that when the latches 20 are down or in alinement 75 with the notches 33 and 39, the tips of the arms 167 will be in a position to engage the pins 168 as shown in Figure 24. When, however, the latches 20 are raised, as shown, for instance, in Figures 32 80 and 33, and in dotted lines Figures 30 and 31, the tip of the arm will be out of the path of the pin 168. Accordingly, when the arms 167 are in the path of the pins 168, depression of the bars 153 will by depressing the 85 slides 164 and by engagement of the arms 167 with the pins 168, cause the frame 161 to move down, thereby moving the main platen M into engagement with the line of type as shown in Figure 30.

The platen M is provided with a stationary guide 173 for guiding the sheet around the platen and a supplemental guide 174 is also provided for further guiding the sheet around the platen, this guide being 100 pivoted on the shaft 175 of the platen and having arms connected by links 176 with slides 177 mounted on the frame 161. Each slide is connected with an arm 178 also pivoted on the carriage and provided with a 105 pin 179 arranged to engage abutments 180 fixed to the end plates of the carriage. The guide 174 is held in normal position enveloping the platen by springs 181 connecting the arms 178 with the frame 161.

The platen M has a ratchet 182 arranged to be engaged by a pawl 183 pivoted on the slide 177 and connected therewith by a spring 184. This pawl has an extension 185 arranged to engage a pin 186 on the frame 110 161. The sheet is further held against the platen by rolls 187 mounted on arms pivoted on the frame 161 and these rolls are held against the platen by springs 188. The roll carrying arms are provided with manipulative parts 189 whereby these rolls may be moved out of engagement with the platen. Mounted for sliding movement on the platen shaft 175 is a frame 190 which is slotted to expose the sheet on the platen and which 115 is arranged to receive a ribbon 191 (see Figure 2).

The latches 20 have projecting therefrom pins 192 arranged to be engaged by cam lugs 193 and 194 on an arm 195 pivoted on 120

130

the slide 164 and held against the pin 192 by a spring 196 connecting the arm with the carriage. Mounted on the carriage end 17 is also a pin 197 arranged in the path of the 5 cams 193 and 194.

The main and supplemental platens are similar in structure and the above description really applies to both platens, except that the supplemental structure and frame 10 does not have the arms 195 and their connections but that it has fixed abutments 198 in the path of the pins 179. It will be noted in this connection that when the latches 20 of the main platen are dropped into the 15 primary locating notches 33 and 39, the tips of the arms 167 are in the path of the pins 168, on the main platen frame 161. The supplemental latches 21 are, however, at this time raised and on the surface of the 20 bars 30 and 35, and the tips of the arms 167 are out of the path of the pins 168 on the supplemental platen frame 161. This also positions the abutments 180 in the path of the pins 179 on the main platen frame. 25 Assuming now that the main and supplemental platens have been successively shifted with the platen carriage from normal position to primary position as noted in full and dotted lines Figures 24 and 25, 30 from primary position to secondary position as shown in full and dotted lines respectively Figures 26 and 27, and from secondary position to tertiary position, as shown in full and dotted lines Figures 28 and 29, the main 35 platen is now in proper location for cooperation with the selective printing line. Accordingly in the tertiary position of the parts, the main platen will be in proper position for cooperation with the printing line, 40 and at this time the actuating connection between the bars 153 and the main platen frame is effectual, while this connection will be ineffectual with reference to the supplemental platen and its frame. 45

When the main platen has been located in final tertiary position by depression of the keys as heretofore described, the auditor will pull forward on the handle 158 thereby causing the bars 153 to move downward. 50 This will by cooperation with the slides 164 and the engagement of the tips of the arms 167 with the pins 168 on the main platen frame 161, move this frame down to the position shown in Figure 30. During 55 this movement the engagement of the pin 179 with the arm 180 will shift the slide 177 down, thereby causing the pawl 183 to engage the ratchet 182 and feed the sheet one space, such feeding movement being stopped 60 by the engagement of the extension 185 with the stop pin 186, moving the pawl out of engagement with the ratchet. The link connection 176 between the slide 177 and the guide 174 will swing this guide from underneath the platen so as to expose the same. 65

As this platen now continues its downward movement, the frame 190 will first engage the printing bed, and as the platen follows, it will by pressing against the ribbon 191 and against the line of type, make an impression on the sheet. 70

As the platen frame moves down the arm 195 will be carried with it, but the cam lugs 193 and 194 will pass freely over the pins 192 and 197 until the shoulder of the cam lug 194 engages beneath the pin 192. When the handle 158 is now released, thereby permitting the bars 153 to move up, the spring 163 in returning the parts back to normal position will cause the arm 195 to be carried 75 with the slide 164 so that the shoulder of the lug 194 in taking underneath the pins 192 will raise the main latches 20, thereby releasing the platen carriage. This platen carriage will, therefore, move from full to 80 dotted position, Figures 30 and 31 until the supplemental latches 21 drop into the alined locating notches 33 and 39 so as to locate the supplemental platen S at the printing line. Towards the end of the upward movements 85 of the arms 195 with the main platen frame, the engagement of the cam lug 193 with the pin 197 will move the shoulders of the cam lugs 194 clear of the pins 193, thereby permitting the main latches 20 again to drop 90 on the upper faces of the bars 30 and 35, as shown in dotted lines, Figures 30 and 31.

Accordingly, the supplemental platen S will now be at the selected printing line, and the supplemental latches in dropping 100 into the alined notches will position the tips of the arms 167 in positions to engage the pins 169 on the supplemental platen frame, while the elevation of the main latches 20 will shift the tips of the arms 167 so as to 105 clear the pins 169 on the main platen frame.

With the parts in the position shown in Figures 30 and 31, the handle 158 is again moved forward, thereby causing the operations to be repeated but on the supplemental platen only, the main platen remaining 110 at rest, and this causes an impression to be made on the ledger sheet on the supplemental platen as noted in Figures 32 and 33. However, it is not necessary at this time to 115 release the supplemental latches upon return of the parts to normal position, since the carriage is returned otherwise as herein-after more fully described.

The motor drive mechanism.

Referring to Figures 1, 2, 34 and 35, the rear end of the frame has encased therein motor drive mechanism comprising a suitable electric motor 210, the shaft of which 125 has a pinion 211 meshing with a gear 212 loose on a shaft 213 mounted in brackets 214 on the base. The shaft has fixed thereto a clutch element 215, having an ordinary ball clutch connection with the gear 212 and 130

provided with teeth 216 engaged by a stop 217. The construction is such that when the stop 217 engages one of the teeth 216, the clutch element 215 as well as the shaft 213 5 will be retained against movement and further movement of the gear 212 will then unclutch it. When, however, the clutch element 215 is released by moving the stop 217 down Figure 35, the gear and the clutch elements will be clutched together so that the shaft 213 will then be driven. This form of ball clutch is well known in the art and further detail description thereof is, therefore, unnecessary.

15 The shaft 213 has fixed thereto a pinion 218 meshing with a gear 219 on a counter-shaft 220 mounted in bearings 221 on the base. Also mounted on this base is a casing 222 which contains one or more coil springs, 20 each of which is connected at one of its ends to the shaft 220 and at the other of its ends to the casing 222, so as to tend to rotate the shaft 220 in a direction opposite the direction of the arrow (Figure 35).

25 The shaft 220 has fixed thereto sprockets 223, each of which carries an endless sprocket chain 224 passing over a sprocket 225 in the forward end of the frame. These sprocket chains are guided by housings 226 30 whereby either a thrust or a tension may be applied to each chain, while they are sustained against buckling. Each sprocket chain has fixed thereto and projecting upwardly therethrough the housing, a connecting element 227 adapted to make connection with the lug 228 on each end of the platen carriage.

The shaft 223 has fixed thereto a gear 229 35 meshing with a pinion 230 on a shaft 231 mounted in bearings 232 on the base and housing 233. This shaft has fixed thereto a rotating element 234 forming a governor for limiting the speed of the shaft 213, so that when the speed exceeds a predetermined amount, a braking force will be applied by elements on the rotating element 234 engaging the housing 233. Such a governor is, however, well known in the art and further detail description is, therefore, unnecessary; suffice it to say that this governor serves to maintain the speed of the shaft 213 at a predetermined value.

The tension of the springs in the casing 222 is such as to apply tension on the sprocket chains 224 in the direction of the arrows Figure 34. Accordingly, a tension will be applied to the carriage tending to move it to the right Figure 2 as previously described. Accordingly, as soon as this carriage is released, these springs will act to move the carriage to the right until arrested as previously described. When, however, the carriage has been so moved and it is desired to return it, the stop 217 is dropped 60 by mechanism hereinafter to be described,

and the release of the clutch element 213 will cause the shaft 213 to be clutched with the motor so that the motor will not only return the carriage, but also again wind up the springs.

The restoring mechanism.

Referring to Figures 1, 2, 3, 4, 34, 35, 36, and 37, mounted between the plates 43 is a shaft 240, which has mounted thereon 75 arms 241 connected by links 242 with arms 243 on a rock shaft 244 provided with an arm 245 connected with a block 246 on the stop 217. A plunger 247 in a casing 248 on the base is acted upon by a spring 249, while the arm 245 is connected with a spring 250 anchored on the bracket 214. The plunger 244 is connected by a link 251 with a cross head 252 guided at 253 on the base, and provided with pins 254 adapted for engagement with pins 255 on the sprocket chains 224.

When the shaft 240 is rocked in the direction of the arrow Figure 2, the link 242 will be moved in the direction of the arrows, 90 Figures 34 and 35 so as to drop the stop 217, which will now be latched in position by the plunger 244 taking over the block 246, it being understood that at this time, the pins 255 will move away from the pins 254 95 so as to permit such movement. Accordingly, the motor is connected with the shaft 220 thereby winding the spring and returning the carriage back to normal position. As the carriage reaches normal position, and assuming that the rock shaft 240 has again been released, the pins 255 will engage the pins 254 on the cross head 252, thereby withdrawing the plunger 247 and permitting the stop 217 to again move in the path of the teeth 216 on the clutch element 215 so as to lock this element against movement and unclutch the motor from the shafts 213 and 220; accordingly, the carriage and all parts will be restored back to normal position. 100 It is to be understood that when the carriage is drawn rearwardly over the printing bed by the springs, the teeth 216 now move opposite to the direction of the arrow Figure 35 and will snap idly over the stop 110 217.

The shaft 240 has fixed thereto arms 260 connected by links 261 with arms 262 pivoted at their lower ends on the base. These arms are connected by links 263 with the pins 264 on movable bars 35, the links 263 being slotted to permit complete rearward movement of these bars. The bars 30 also have lugs 265 taking behind the bars 35.

Upon movement of the rock shaft 240 125 in the direction of the arrow Figure 2, it will operate through the arms and links 260, 261, 262 and 263 to return the bars 35 and 30 back to normal position, it being understood that the movement is first of the bars 130

35, then of the members 24, and then by engagement of the members 40 with the links 265, the bars 30 are returned. This will also return the arms 61 and 89 back to normal positions, the pins 60 and 88 on these arms engaging the beveled portions 59 and 87 on the arms 58 and 86 respectively, thereby causing these arms to swing; the pins then taking behind the arms, it being understood that just prior to this time, the stops 47 and 74 will be returned as will be hereinafter described. Furthermore, the pin 88 in returning to normal position will strike against a projection 266 (Figures 13, 15 16 and 17) so as to return the frame 71 back to normal position, the engagement of the beveled surfaces 108 and 109, Figure 18, causing the latch 103 to swing and then take in front of the frame so as to return 20 and lock this frame in normal position.

One of the arms 51 on the rock shaft 52 (see Figure 9) has an ear 270 projecting through an opening 271 in the side plate 43 and arranged in the path of a lug on 25 a slide 273, mounted for sliding movement on pins 274 on the side plate 43 and connected with an arm 275 on the rock shaft 240. One of the arms 78 (Figure 15) also has an ear 276 projecting through an aperture 277 in the plate 43 and arranged in the path of a lug 278 on the arm 245. When the rock shaft 240 is moved in the direction of the arrow, Figure 36, the engagement of the lugs 272 and 278, with the ears 270 35 and 276 on the arms 51 and 78 respectively, depressed stops 47 and 74 will be released so as to cause their springs to return them back to normal positions, this action occurring just prior to the engagement of the pins 60 and 88 with the beveled portions of the arms 58 and 86 as heretofore described. Accordingly, the stops will be returned back to 40 normal positions and the other locating devices will also be returned back to normal 45 positions.

The rock shaft 240 has an arm similar to the arm 275 fixed to the other end thereto and this arm also engages with a similar slide 273 also mounted by pins 274 on the 50 plate 43. Each slide has an extension 279 connected with the transmitter carrier 122, the rolls 123 of which are guided in guides 280 in the plates 43 as heretofore described. Upon movement of the arm shaft 240 in 55 the direction of the arrows Figures 36 and 37, the transmitter carrier 122 will be returned back to normal position against the tension of the spring 130, and will be latched in that normal position by the pawl 134 taking in front of the first stop or tooth 131 (Figure 12).

The rock shaft 240 has fixed thereto segments 281 meshing with segments 282 on a counter shaft 283 mounted in the plates 43, 60 and this counter shaft has fixed thereto or

the segments 281 have integral therewith, arms 284 carrying a handle 285, these arms moving through slots in the top of the casting. The arms 284 are held in normal position by one or more springs 286 connected with the arm or arms 284 and anchored on a plate or plates 43.

The segment 282 is provided with a tooth portion and with a plain convex portion 287, while the segment 281 is provided with a tooth portion and a concave portion 288. Hubs 289 on the rock shaft 283 are provided with teeth 290 arranged to engage pawls 291 pivoted at 292 on the plates 43, and having arms 293 held in the path of the rolls 123 on the transmitter carriage 122 by springs 294 connected with the arms and anchored on the plates 43.

The pawls 291 normally operate to lock the shaft 283 against movement and these pawls are so retained until the transmitter carriage has moved through two complete steps so as to complete the tertiary key depression and accordingly, there cannot be effected a movement of the handle until a tertiary key has been depressed, at which time the complete movement of the transmitter carriage will lift the pawls out of engagement with the teeth 290. Accordingly, the handle cannot be moved to clear the machine until a complete item has been set up on the key board comprising primary, secondary and tertiary operations of the keys. It will, however, be noted that on account of the interrupted portions 287 and 288 of the 100 segments, there can be an initial movement of the handle and of the shaft 283 and its segments 282 before the shaft 240 is rocked. Accordingly, the teeth 290 can move underneath the pawl before the transmitter carrier is moved.

Résumé of operations.

Let us assume that it is desired to make a statement and enter in the ledger the taxes 110 for a principal item of, for instance, \$295.00. The auditor will insert in the main platen a statement sheet and in the supplemental platen a ledger sheet. Where the machine is not provided with a ribbon, then a piece 115 of carbon paper can be inserted with each sheet so as to obtain an impression in that way. The carriage being in normal position, the auditor will successively depress keys "2", "9" and "5", when the operations 120 will be as follows:

The depression of the "2" key will depress the "2" stop 47 (Figure 7) in to the path of the arm 61 and concurrently will move the arm 58 to release the stop 60 thereon, so as to cause the spring 67 to shift the movable bars 35 until the locating elements 33 and 39 corresponding to the "200" or primary position are in alinement; the carriage will now move under the tension of 130

its spring forwardly until arrested by these alining elements in the primary "200" position as noted in dotted lines, Figures 24 and 25. Upon depression of the "9" key, the 5 "9" stop 74 (Figure 13) will be depressed into the path of the arm 89 and concurrently this arm will be released, and the tension of the main spring on the carriage will 10 carry both bars 30 and 35 rearwardly until arrested in the "9" secondary position as noted in dotted lines Figures 26 and 27. The depression of the "5" key will now cause the depressed "9" stop 74 to be moved with the frame through a half step (Figure 16) 15 thereby causing the tension of the spring on the carriage to move the carriage rearwardly one-half step until finally arrested in tertiary located position as noted in dotted lines, Figures 28 and 29.

20 The auditor will now pull forwardly on the handle 158. This will cause the main platen to move down on the line of type corresponding to "295" with which it has been 25 alined so as to make an impression on the statement, the paper being fed previously to making such impression. Upon release of the handle 158, the main platen is not only raised back to normal position, but the entire carriage is shifted so as to cause the 30 supplemental platen to now aline with the line of type identified by the number "295", as shown in dotted lines Figures 30 and 31 and in full lines Figures 33 and 32. Upon again pulling forward on the handle 158, 35 the supplemental platen is moved down to cooperate with the line of type and to make an impression on the ledger sheet as shown in Figures 32 and 33. Upon the return of the handle 158, the supplemental platen is 40 returned back to normal position.

The auditor will now pull forward on the handle 285 (Figure 1). This operation will first connect the motor with the carriage so as to start this carriage upon its return, and 45 will then shift the bars 30 and 35 back to normal positions, with their arms 61 and 89 latched in normal position, it being understood that the stops are released after the beginning of the movement of the arms back 50 to normal position, but before the completion of such return. The transmitter carrier is also returned back to normal position. This will return all parts to normal positions, and upon releasing the handle 285, 55 the springs 286 return the handle and this handle is then latched by the pawls 291. As the carriage returns to normal position, the motor is disconnected from the carriage by the release of the plunger 244 (Figure 35) 60 and if the carriage has been moved too far, it will return a short distance until the main latches again take into the alined "0" locating elements or notches in the bars 30 and 35.

65 If there is only one series of items to be

made, the statement can be removed from the main platen and it will then have the appearance as shown in Figure 38. The ledger sheet may, however, be retained in the supplemental platen for successive entries, and this is also true of the main platen as successive entries may be made on the statement.

It will, therefore, be seen that the invention accomplishes its objects. By the simple depression of keys corresponding to the principal item, not only can this principal item be printed not only on the statement but also in a ledger. The machine will operate with an unfailing accuracy of mechanism in general and there can be no mistake made, except in the depression of the keys, which is exceedingly remote. Accordingly, the laborious task of posting of items, which heretofore has in the greater number of instances been only accomplished manually, is avoided by the use of a machine embodying this invention.

While an embodiment of this invention has been shown and described as applied to a tax computing machine, it is to be understood that this is simply for the purpose of illustration, since the invention is broadly applicable for embodiment in machines for accomplishing various classes of posting.

It will further be obvious that various changes may be made in details of construction without departing from the spirit of this invention; it is, therefore, to be understood that this invention is not to be limited to the specific details shown and described.

Having thus described the invention, what is claimed is:

1. A machine of the character described, comprising, a printing bed, a platen, and means adapted to selectively locate said platen with respect to selected positions on said bed.

2. A machine of the character described, comprising, a printing bed having printing lines, a platen extending along said lines, and means for locating said platen for cooperation with selected lines.

3. A machine of the character described, comprising, a printing bed having printing lines extending thereacross, a platen extending along said lines, and means for locating said platen along said bed to cooperate with selected lines.

4. A machine of the character described, comprising, a printing bed, a platen, means adapted to locate said platen with respect to said bed, and selective manipulative means adapted to control said locating means.

5. A machine of the character described, comprising, a printing bed having printing lines, a platen extending along said lines, and selective manipulative means for locating said platen for cooperation with selected lines.

6. A machine of the character described, comprising, a printing bed, a platen, and means for effecting cooperation of said platen with a selected part of said bed.
- 5 7. A machine of the character described, comprising, a printing bed having printing lines, a platen, and means for effecting cooperation of said platen with a selected line.
- 10 8. A machine of the character described, comprising, a printing bed, a platen, means for relatively locating said platen and said bed, and selective manipulative means for controlling said locating means.
- 15 9. A machine of the character described, comprising, a printing bed, a platen extending across said bed, means for causing cooperation of said platen with parts along said bed, and selective manipulative means for effecting such cooperation.
- 20 10. A machine of the character described, comprising, a printing bed having printing lines, a platen, means for effecting cooperation of said platen with said lines, and selective manipulative means for effecting such cooperation.
- 25 11. A machine of the character described, comprising, a printing bed, a platen, means for locating said platen to positions along said bed, and selective manipulative means for effecting such locations.
- 30 12. A machine of the character described, comprising, a printing bed having printing lines extending thereacross a platen extending across said bed, means for locating said platen along said bed, for cooperation with said lines, and selective manipulative means for effecting such locations.
- 35 13. A machine of the character described, comprising, a printing bed, a platen, means for primarily locating said platen with respect to said bed, and means for secondarily locating said platen with respect to said bed.
- 40 14. A machine of the character described, comprising, a printing bed, a platen, means for primarily locating said platen with respect to said bed, means for secondarily locating said platen with respect to said bed, and means for tertiary locating said platen with respect to said bed.
- 45 15. A machine of the character described, comprising, a printing bed, a platen, means for causing cooperation of said platen with parts of said bed, and primary and secondary locating means for effecting such cooperation.
- 50 16. A machine of the character described, comprising, a printing bed, a platen, means for causing cooperation of said platen with parts of said bed, and primary, secondary and tertiary locating means for effecting such cooperation.
- 55 17. A machine of the character described, comprising, a printing bed having printing lines, a platen, means for causing cooperation of said platen with said lines, and pri-
- mary and secondary locating means for effecting such cooperation.
- 60 18. A machine of the character described, comprising, a printing bed having printing lines, a platen, means for causing cooperation of said platen with said lines, and primary, secondary and tertiary locating means for effecting such cooperation.
- 65 19. A machine of the character described, comprising, a printing bed having printing lines, a platen, means for causing cooperation of said platen with said bed, means for primarily and secondarily locating such cooperation, and selective manipulative means for effecting such cooperation.
- 70 20. A machine of the character described, comprising, a printing bed having printing lines, a platen, means for causing cooperation of said platen with said bed, means for primarily, secondarily and tertiary locating such cooperation, and selective manipulative means for effecting such cooperation.
- 75 21. A machine of the character described, comprising, a printing bed, a platen mounted for movement therealong, means for primarily locating said platen, and means for secondarily locating said platen.
- 80 22. A machine of the character described, comprising, a printing bed, a platen mounted for movement therealong, means for primarily locating said platen, means for secondarily locating said platen, and means for tertiary locating said platen.
- 85 23. A machine of the character described, comprising, a printing bed, a platen mounted for movement therealong, means for primarily locating said platen, means for secondarily locating said platen, and selective manipulative means for effecting such location.
- 90 24. A machine of the character described, comprising, a printing bed, a platen mounted for movement therealong, means for primarily locating said platen, means for secondarily locating said platen, means for tertiary locating said platen, and selective manipulative means for effecting such location.
- 95 25. A machine of the character described, comprising, a printing bed, a platen mounted for movement therealong, means for primarily locating said platen, means for secondarily locating said platen, and means for effecting cooperation of the located platen with said bed.
- 100 26. A machine of the character described, comprising, a printing bed, a platen mounted for movement therealong, means for primarily locating said platen, means for secondarily locating said platen, means for tertiary locating said platen, and means for effecting cooperation of the located platen with said bed.
- 105 27. A machine of the character described, comprising, a printing bed, a platen mount-

ed for movement therealong, means for locating said platen, and means for effecting cooperation of the located platen with said bed.

5 28. A machine of the character described, comprising, a printing bed, a series of platens, and means for causing cooperation of said platens with said bed.

10 29. A machine of the character described, comprising, a printing bed, a series of platens, and means for causing said platens to cooperate successively with said bed.

15 30. A machine of the character described, comprising, a printing bed, a series of platens, means for causing one of said platens to cooperate with said bed, and means for causing the other platen to cooperate with said bed.

20 31. A machine of the character described, comprising, a printing bed, a series of platens, and means for causing cooperation of said platens with selected parts of said bed.

25 32. A machine of the character described, comprising, a printing bed, a series of platens, means for causing one of said platens to cooperate with a selected part of said bed, and means for causing the other platen to cooperate with said part.

30 33. A machine of the character described, comprising, a printing bed, a series of platens, and means for causing said platens to cooperate successively with selected parts of said bed.

35 34. A machine of the character described, comprising, a printing bed, a series of platens, means for causing cooperation of said platens with said bed, and selective manipulative means for effecting such co- operation.

40 35. A machine of the character described, comprising, a printing bed, a series of platens, means for causing one of said platens to cooperate with a selected part of said bed, means for causing the other platen to cooperate with said part, and selective manipulative means for effecting such co-operation.

45 36. A machine of the character described, comprising, a printing bed, main and supplemental platens, means for causing said main platen to cooperate with said bed, and means for causing said supplemental platen to thereafter cooperate with said bed.

50 37. A machine of the character described, comprising, a printing bed, main and supplemental platens, means for causing said main platen to cooperate with a selected part of said bed, and means for causing said supplemental platen to thereafter cooperate with said part.

55 38. A machine of the character described, comprising, a printing bed, main and supplemental platens, means for causing said main platen to cooperate with said bed, means

for causing said supplemental platen to thereafter cooperate with said bed, and selective manipulative means for effecting such cooperation.

60 39. A machine of the character described, comprising, a printing bed, main and supplemental platens mounted for movement along said bed, means for locating said main platen, and means for locating said supplemental platen at the location of said main platen.

65 40. A machine of the character described, comprising, a printing bed, main and supplemental platens mounted for movement along said bed, means for locating said main platen in selected positions, and means for locating said supplemental platen at such positions.

70 41. A machine of the character described, comprising, a printing bed, main and supplemental platens mounted for movement along said bed, means for locating said main platen, means for locating said supplemental platen at the location of said main platen, and means for effecting cooperation of said located platens with said bed.

75 42. A machine of the character described, comprising, a printing bed, main and supplemental platens mounted for movement along said bed, means for locating said main platen in selected positions, means for locating said supplemental platen at such positions, and means for effecting cooperation of said platen with said bed at such positions.

80 43. A machine of the character described, comprising, a printing bed, main and supplemental platens mounted for movement along said bed, means for locating said main platen, means for locating said supplemental platen at the location of said main platen, and selective manipulative means for effecting such locations.

85 44. A machine of the character described, comprising, a printing bed, main and supplemental platens mounted for movement along said bed, means for locating said main platen, means for locating said supplemental platen at the location of said main platen, selective manipulative means for effecting such locations, and means for effecting cooperation of said located platens with said bed.

90 45. A machine of the character described, comprising, a printing bed, main and supplemental platens, means for causing said main platen to cooperate with said bed, and means operating upon such cooperation adapted to cause said supplemental platen to cooperate with said bed.

95 46. A machine of the character described, comprising, a printing bed, main and supplemental platens, means for causing said main platen to cooperate with a selected part of said bed, and means operating upon such cooperation adapted to cause said sup-

plemental platen to cooperate with said part.

47. A machine of the character described, comprising, a printing bed, main and supplemental platens, means for locating said main platen with respect to a selected part of said bed, and means for locating said supplemental platen with respect to said part.

48. A machine of the character described, comprising, a printing bed, main and supplemental platens, means for locating said main platen with respect to a selected part of said bed, means for effecting cooperation of the located main platen with said part, and means for locating said supplemental platen with respect to said part.

49. A machine of the character described, comprising, a printing bed, main and supplemental platens, means for locating said main platen with respect to a selected part of said bed, means for effecting cooperation of the located main platen with said part, and means adapted upon such cooperation for locating said supplemental platen with respect to said part.

50. A machine of the character described, comprising, a printing bed having type of principal and related items, and a platen adapted for cooperation with the type of a selected principal and its related items.

51. A machine of the character described, comprising, a printing bed having type of principal and related items, a platen, means adapted to cause cooperation of said platen with the type of a selected principal and its related items, and selective manipulative means adapted to effect such cooperation.

52. A machine of the character described, comprising, a printing bed having type of principal and related items, a platen, means adapted to cause cooperation of said platen with the type of a selected principal and its related items, and selective manipulative means corresponding to said principal items, adapted to effect such cooperation.

53. A machine of the character described, comprising, a printing bed having type of principal and related items, a platen, means for locating said platen with respect to the type of a principal and its related items, and selective manipulative means adapted to effect such location.

54. A machine of the character described, comprising, a printing bed having type of principal and related items, a platen, means for locating said platen with respect to the type of a principal and its related items, selective manipulative means adapted to effect such location, and means for effecting cooperation of said platen with the type of said items.

55. A machine of the character described, comprising, a printing bed having type of

principal and related items, a platen, means for locating said platen with respect to the type of a principal and its related items, and selective manipulative means corresponding to said principal items adapted to effect such location.

56. A machine of the character described, comprising, a printing bed having printing lines containing each a principal and related items, a platen, means adapted to cause cooperation of said platen with a selected line, and selective manipulative means adapted to effect such cooperation.

57. A machine of the character described, comprising, a printing bed having printing lines containing each a principal and related items, a platen, means adapted to cause cooperation of said platen with a selected line, and selective manipulative means corresponding to the principal items adapted to effect such cooperation.

58. A machine of the character described, comprising, a printing bed having printing lines containing each a principal and related items, and a series of platens adapted for successive cooperation with the type of said items.

59. A machine of the character described, comprising, a printing bed having printing lines containing each a principal and related items, and a series of platens adapted for successive cooperation with the type of a selected principal and its related items.

60. A machine of the character described, comprising, a printing bed having printing lines containing each a principal and related items, and a series of platens adapted for successive cooperation with a selected line.

61. A machine of the character described, comprising, a carriage having a plurality of elements, means for primarily locating said carriage, means for secondarily locating said carriage, means for locating an element on said carriage, and means for locating another element on said carriage.

62. A machine of the character described, comprising, a carriage having a plurality of elements, means for primarily locating said carriage, means for secondarily locating said carriage, means for tertiary locating said carriage, means for locating an element on said carriage, and means for locating another element on said carriage.

63. Mechanism of the character described, comprising, a locating member having a series of locating elements, means for primarily locating said member, and means for secondarily locating said member.

64. Mechanism of the character described, comprising, a locating member having a series of spaced locating elements, means for rendering a selected element effective, means for primarily locating said member, and means for secondarily locating said member.

65. Mechanism of the character described, comprising, a locating member having a series of spaced locating elements, a movable member having a series of spaced locating elements adapted for selective cooperation with said first elements, means for primarily locating said members, and means for secondarily locating said members.
- 10 66. Mechanism of the character described, comprising, a locating member having a series of spaced locating elements, a movable element having a series of spaced locating elements, the spacings of said second elements being a definite fraction of the spacings of said first elements, means for selectively locating said movable member, and means for selectively locating said members.
- 15 67. Mechanism of the character described, comprising, a locating member having a series of spaced locating elements, an element extending along said first element and having a series of spaced locating elements, the aggregate spacings of said second elements being equal to the aggregate spacings less one of said first elements, means for primarily locating said members, and means for secondarily locating said members.
- 20 68. Mechanism of the character described, comprising, a locating member having a series of spaced locating elements, a movable member adapted to render a selected element effective, means for selectively locating said movable member, and means for selectively locating said members.
- 25 69. Mechanism of the character described, comprising, a locating member having a series of spaced locating elements, a movable member adapted to render a selected element effective, means for selectively locating said movable member, means for primarily locating said members, and means for secondarily locating said members.
- 30 70. Mechanism of the character described, comprising, a locating member having a series of spaced locating elements, a movable member having a series of spaced locating elements adapted for selective cooperation with said first elements, means for selectively locating said movable member, and means for selectively locating said members.
- 35 71. Mechanism of the character described, comprising, a locating member having a series of spaced locating elements, a movable member having a series of spaced locating elements adapted for selective cooperation with said first elements, means for selectively locating said movable member, means for primarily locating said members, and means for secondarily locating said members.
- 40 72. Mechanism of the character described, comprising, a locating member having a series of spaced locating elements, a movable member adapted to render a selected element effective, means for selectively locating said movable member, means for primarily locating said members, and means for secondarily locating said members.
- 45 73. Mechanism of the character described, comprising, a locating member having a series of spaced locating elements, a movable element having a series of spaced locating elements, the aggregate spacings of said second elements being equal to the aggregate spacings less one of said first elements, means for selectively locating said movable member, and means for selectively locating said members.
- 50 74. Mechanism of the character described, comprising, a locating member having a series of spaced locating members, an element extending along said first element and having a series of spaced locating elements, the aggregate spacings of said second elements being equal to the aggregate spacings less one of said first elements, means for selectively locating said second member, and means for selectively locating said members.
- 55 75 76. Mechanism of the character described, comprising, a locating member having a series of spaced locating elements, an element extending along said first element and having a series of spaced locating elements, the aggregate spacings of said second elements being equal to the aggregate spacings less one of said first elements, means for selectively locating said second member, and means for selectively locating said members.
- 60 77. Mechanism of the character described, comprising, a locating member having a series of spaced locating elements, a movable member having a series of spaced locating elements adapted for selective operation with said first elements, means for primarily locating said members, means for secondarily locating said members, and selective manipulative means for effecting such locations.
- 65 78. Mechanism of the character described, comprising, a locating member having a series of spaced locating elements, a movable member adapted to render a selected element effective, means for selectively locating said movable member, means for primarily locating said members, and means for secondarily locating said members.

secondarily locating said members, and selective manipulative means for effecting such locations.

79. Mechanism of the character described, comprising, a locating member having a series of spaced locating elements, a movable member having a series of spaced locating elements adapted for selective cooperation with said first elements, means for selectively locating said movable member, means for primarily locating said members, means for secondarily locating said members, and selective manipulative means for effecting such locations.

15 80. Mechanism of the character described, comprising, a locating member having a series of spaced locating elements, a movable element having a series of spaced locating elements, the spacings of said second elements being a definite fraction of the spacings of said second elements, means for selectively locating said movable member, means for primarily locating said members, means for secondarily locating said members, and selective manipulative means for effecting such locations.

30 81. Mechanism of the character described, comprising, a locating member having a series of spaced locating elements, an element extending along said first element and having a series of spaced locating elements, the aggregate spacings of said second elements being equal to the aggregate spacings less one of said first elements, means for primarily locating said members, means for secondarily locating said members, and selective manipulative means for effecting such locations.

40 82. Mechanism of the character described, comprising, a shiftable device, means for locating said device at a series of primary positions, means for locating said device at a series of secondary positions, means for locating said device at a series of tertiary positions, and means for shifting said device.

50 83. Mechanism of the character described, comprising, a shiftable device, means for locating said device at a series of primary positions, means for locating said device at a series of secondary positions, means for locating said device at a series of tertiary positions, means for shifting said device, and means for restoring said device.

55 84. Mechanism of the character described, comprising, a shiftable device, means for locating said device at a series of spaced positions, means for locating said device at a series of spaced positions between each of the spacings of said first positions, and means for shifting said device.

60 85. Mechanism of the character described, comprising, a shiftable device, means for lo-

cating said device at a series of spaced positions, means for locating said device at a series of spaced positions between each of the spacings of said first positions, means for shifting said device, and means for restoring said device.

70 86. Mechanism of the character described, comprising, a shiftable device, means for locating said device at a series of spaced positions, means for locating said device at a series of spaced positions between each of the spacings of said first positions, means for locating said device at positions between each of the spacings of said second positions, and means for shifting said device.

80 87. Mechanism of the character described, comprising, a shiftable device, means for locating said device at a series of spaced positions, means for locating said device at a series of spaced positions between each of the spacings of said first positions, means for locating said device at positions between each of the spacings of said second positions, means for shifting said device, and means for restoring said device.

90 88. A machine of the character described, comprising, a carriage, means for setting up primary and secondary locations, and means for moving said carriage to the final location.

95 89. A machine of the character described, comprising, a carriage, means for setting up primary, secondary and tertiary locations, and means for moving said carriage to the final location.

100 90. A machine of the character described, comprising, a carriage, means for setting up primary and secondary locations, and means for automatically locating said carriage at the final location.

105 91. A machine of the character described, comprising, a carriage, means for setting up primary, secondary and tertiary locations, and means for automatically locating said carriage at the final location.

110 92. A machine of the character described, comprising, a carriage, means for setting up primary and secondary locations, means for automatically locating said carriage at the final location, and selective manipulative means for effecting such settings.

115 93. A machine of the character described, comprising, a carriage, means for setting up primary, secondary and tertiary locations, means for automatically locating said carriage at the final location, and selective manipulative means for effecting such settings.

In testimony whereof I affix my signature this 16th day of March, 1920.

LUTHER A. WATTERS.
